J. L. LAWRENCE.
INTERNAL COMBUSTION ENGINE.
APPLICATION FILED FEB. 16, 1912.

1,178,737.

Patented Apr. 11, 1916.

UNITED STATES PATENT OFFICE.

JAMES LOUIS LAWRENCE, OF MEXICO, MEXICO, ASSIGNOR OF ONE-HALF TO CHARLES L. SEEGER, OF MEXICO, MEXICO.

INTERNAL-COMBUSTION ENGINE.

1,178,737.

Specification of Letters Patent. Patented Apr. 11, 1916.

Application filed February 16, 1912. Serial No. 678,098.

To all whom it may concern:

Be it known that I, JAMES L. LAWRENCE, a citizen of the United States, residing in the city of Mexico, Republic of Mexico, have made a certain new and useful Invention in Internal-Combustion Engines, of which the following is a specification.

This invention relates to internal combustion engines.

10 The object of the invention is to simplify and improve the construction of internal combustion engines, to render the same more efficient in operation, more economical to manufacture, and more readily and easily 15 dismembered for repair.

Other objects of the invention will appear more fully hereinafter.

The invention consists substantially in the construction; combination, location, and relative arrangement of parts, all as will be 20 more fully hereinafter set forth, as shown in the accompanying drawings, and finally pointed out in the appended claim.

In the accompanying drawings, Figure 1 25 is a longitudinal central sectional view of an internal combustion engine embodying the principles of my invention. Fig. 2 is a view partly in elevation and partly in section, of the same, showing the relation 30 of the main shaft and the eccentric shaft for operating the valve sleeves.

The same part is designated by the same reference numeral wherever it occurs.

In the drawing 1, is the engine cylinder, 35 which is mounted on or secured to a base portion or casing 22, the latter serving as the crank case. The cylinder is open at both ends. The end thereof which is secured to the casing 22, opens into or communicates 40 freely with the interior of the casing 22. If desired, and preferably, the cylinder is constructed with a jacket chamber 2 for the circulation of water or other cooling medium. The piston 3 operates in the cylinder 45 1, and is connected by connecting rod 4 to crank pin 5, of crank 24, of the main power shaft 25, the said shaft extending through the casing 22, and the crank 24 being located within said casing. The connecting 50 rod 4 extends through the casing 22 and into the open end of the cylinder where it is pivotally connected to the piston in the usual or any well known manner.

The outer open end of the cylinder is

closed by a head or cap 9, adapted to be 55 bolted or otherwise secured onto the end of the cylinder, as, for instance, by means of the cap screens 14. If desired, and preferably, the head or cap 9 is constructed with a jacket chamber 12, for the circulation of 60 water or other cooling medium. A spark plug or other charge igniting device 8 is arranged to project through the head or cap 9 into the end of the cylinder. The cylinder head or cap 9, is provided with a depending petticoat or rim portion 26, which is of larger internal diameter than the external diameter of the cylinder, and this depending rim portion or petticoat 65 encompasses the cylinder for a considerable 70 portion of its length having a space or open ended chamber 27, between the exterior surface of the cylinder and the interior surface of the rim portion or petticoat of the head or cap. The cooling chamber 12, formed in 75 the head or cap 9, also continues into the rim portion or petticoat 26.

I have not shown the connections for supplying or circulating the cooling medium, to or through the cylinder and head or cap 80 jackets 2, 12, as such details form no part of my present invention and are familiar to persons skilled in the art.

Nested or telescoped, the one inside the other and upon the exterior surface of the 85 cylinder are the valve sleeves 17, 18, said sleeves being arranged to extend into and to operate in the annular space 27 between the cylinder and the depending rim 26, of the head or cap 9. The sleeves 17, 18, are 90 mounted to slide or to reciprocate longitudinally, relatively to each other and to the cylinder. Any suitable or convenient means may be employed to reciprocate the sleeves. A simple arrangement is shown wherein 95 connecting rods 15, 16, are respectively connected to said sleeves 17, 18, and to cranks 20, 19 on a counter shaft 28, driven from the power shaft 25, by any suitable arrangement of gearing connections, as for instance, a 100 sprocket chain 7, operating over sprockets 6, 21, respectively carried by shafts 25, 28. The gear connections intermediate the shafts 25, 28 should bear such relation as to properly time the valve sleeve operating shaft 105 28, and hence the valve sleeve movements, with reference to the main piston movements to secure the desired timing of sup-

ply of explosive charge and escape of the gases of explosion, in a manner well understood in the art.

The explosive mixture is supplied to the cylinder and the gases of explosion are exhausted from the cylinder through the port openings 10, 11, which are provided through the cylinder and extension of the head or cap and also through the valve sleeves, and which are controlled by the sliding movements of the valve sleeves. The fuel supply and exhaust connections may be secured to the depending rim portion of the cap 9, by flanges 13, or in any other suitable or convenient manner. If desired, and preferably, an inclosing shield or casing 35, may be arranged to surround the valve sleeves 17, 18 to exclude dust and dirt from the working or bearing surfaces thereof.

From the foregoing description it will be seen that I employ a fixed cylinder and I place the valve sleeves upon the exterior surface thereof in surrounding or encompassing relation with reference thereto. It will also be seen that I arrange the depending extension rim or petticoat of the cap or head to form a guide inside of which the valve sleeves operate, the said extension or rim encompassing or surrounding the said valve sleeves. It will also be seen that I provide a construction which is very simple and easy to manufacture since I avoid the necessity for any special form of casting. The cooling jackets or chambers of the head and cylinder enable me to maintain the explosion chamber wholly inclosed within a double jacket since the extension or rim of the head or cap surrounds the explosion end of the cylinder. I avoid the provision of any moving part within the cylinder except the piston which may be of the ordinary kind such as is commonly used in gasolene engines. In order to gain access to the cylinder for cleaning or repair, or to remove the valve sleeves, it is only necessary to take off the cylinder head or cap, and disconnect the sleeves from their connecting rods. It will also be seen that the crank case chamber in which the cranks operate may be employed as a receptacle for lubricating oil, the splash of which from the crank rota-

tions constantly supplies such oil to lubricate the working piston. The chamber or space 27, may likewise be employed as an oil chamber to supply lubricating oil to the bearing surfaces of the cylinders. It will also be seen that all packing rings, except those of the piston, are avoided, as the valve sleeves are exposed to the force of the explosion only in the space of the ports 10, 11. The valve sleeves being thus removed from contact with the heated gases, and a water or cooling jacket being interposed between them and the explosion chamber, may be made quite short in length, thereby reducing the friction to a minimum, avoiding the use of packing rings therefor, and reducing the power required to operate them to the lowest possible point.

Having now set forth the object and nature of my invention and a construction embodying the principles thereof, what I claim as new and useful and of my own invention, and desire to secure by Letters Patent is—

In an internal combustion engine, a cylinder and piston and a crank shaft connected to the piston, said cylinder having port openings and constructed with a surrounding cooling jacket or chamber in combination with a head adapted to be applied to one end of the cylinder to close the same and having an integral depending rim portion or petticoat arranged to encompass and surround the exterior surface of the cylinder end, said head and its depending rim portion constructed with an internal space or chamber for the circulation of a cooling medium therethrough, valve sleeves telescoped the one inside the other and upon the exterior surface of the cylinder, and means for reciprocating said sleeves to control said port openings.

In testimony whereof I have hereunto set my hand in the presence of the subscribing witnesses, on this 7th day of February A. D., 1912.

JAMES LOUIS LAWRENCE.
